MARKING GAUGE

Edwin John Roos, Chicago, Ill.

Application May 12, 1941, Serial No. 393,011

My invention relates to marking tools or gauges and while not limited to such use, is particularly designed as a metal marking tool or line gauge for marking or scribing various exact measurements on metals, metal sheets or other material for marking or lining the edges of sheets for cutting, bending or other purposes by tinners, machinists or workers in other fields or with various materials.

Another object of the invention is to provide a simple, handy, efficient and accurate marking tool or gauge which can be conveniently used and which will give exact markings or measurements in any desired standard of measurement such as one-eighth inch to one inch or otherwise so that the metal sheet or material may be marked from the edges for performing any operation in connection therewith, such as in cutting, bending, notching, forming or otherwise.

Another object of the invention is to provide a simple and economical marking tool or gauge which is preferably, though not necessarily, made from a sheet of hardened spring steel or the like to produce sharp marking, scraping or cutting edges or corners for producing a scratching mark upon metal or other material and which obviates the necessity of employing a separate marking tool or pencil.

Other objects and advantages will appear and be brought out more fully in the following specification, reference being had to the accompanying drawing, in which:

Fig. 1 is a perspective view of a marking tool or gauge made in accordance with the invention and showing the same in use;

Fig. 2 is a face view thereof and showing, in addition, a slight modification; and

Fig. 3 is an edge view of the tool or gauge. Referring to the drawings more particularly, it will be seen that the device comprises a flat plate 18 which may be of any suitable material but is preferably of hardened spring steel which may be of 18 or other gauge and chrome plated or otherwise treated to render the same impervious to rust or corrosion. While preferably of hardened steel or other suitable metal so as to bite or cut into ordinary sheet metal, such as galvanized iron, tin or the like, it may be used in connection with other metals, such as steel, copper or other materials such as wood, Bakelite or other plastic material and consists generally of a plate of regular or irregular form with a surrounding convex edge relatively circular but substantially elliptical or oval with a dove-tailed extension at one end and with a plurality of acute

angled notches or cutouts on its edge around the margin, periphery or boundary thereof, which notches of acute angled formation are substantially of sixty degrees, more or less, and include 5 triangular cutouts having one edge forming a base and another edge forming a hypotenuse of a right angled triangle erected on the base, the free ends of which, if connected, produce a triangle. The acute angle formation of the 10 notch is such that when the gauge is placed with its base edge at an intersecting angle either at an acute angle as shown, or perpendicular or normal to the surface to be marked as seen in Fig. 1 and the edge forming the hypotenuse 15 overlying said surface also preferably perpendicular to the edge of the material or sheet and the plate perpendicular or at right angles to the plane of said surface which it intersects at the edge thereof, a line or plurality of markings 20 may be made on said surface equidistantly from or parallel to the edge of the surface engaged by the base edge of the notch and from which said markings are calculated or made. The plate may be provided with suitable means for 25 conveniently gripping or lifting it as well as suspending it, and for the latter purpose may have a relatively central or otherwise arranged hole 30 shown circular for suspending the same from a hook or nail through the body of the plate. As shown, the plate which as before stated, is 35 relatively circular but substantially oval or elliptical in plan, is provided with an extension 12 at one end, namely, the tapered or small end or at its peripheral edge which may be said to form a handle, this extension being preferably 40 of dove tail or fan tail shape as shown with a tapered end 13 or two edges at obtuse angles relative to each other and merging in a point. At one side of the extension 12 which is primarily 45 for larger measurements and markings is an acute angled notch 14 preferably of 60 degrees, more or less, and having an edge portion 15 at one side of the extension 12 forming the hypotenuse of a triangle produced by the notch in 50 connection with the base edge 16 disposed at acute angles relative to the edge 15 so that the notch or cut out will form a triangle by a line connecting the outer ends of the respective edges 15 and 16. This produces a marking point or 55 sharp corner 17 at the meeting point or juncture of one edge portion 13 and the edge 16 so that a strip or sheet of material placed perpendicular to the base edge 16 and in contact with the point 17 at one surface will give an exact measurement 60 from the base to said point which, in the form

shown, is three-quarters of an inch but which may be any desired measurement and in accordance with any desired linear scale. This also produces a right angle triangle between said surface or sheet, the edge 15 and the inner portion of the edge 16 with the material or sheet to be marked normal to the plane of the plate 10 corresponding to the extension or tapered projection 12 particularly as defined by one edge 13 and the edge 15 at one side insofar as it is operative in connection with the notch 14, edges 15 and 16 and marking point 17. It also forms a tapered extension, projection or tooth 18 along the base 16 and with an adjacent acute angled notch 19 having a long edge 20 corresponding to the long edge 15 and forming the hypotenuse of an adjacent triangular or V-shaped notch. The base edge is indicated at 21 and the resulting marking point or corner 22 at the meeting point of the edges 16 and 20 if used in the manner previously described, will give a measurement, marking or line five-eighths of an inch from the edge of the sheet or material to be marked when the tool or gauge is moved along one edge thereof under slight pressure as indicated in Fig. 1 of the drawing.

In a similar manner, a plurality of successive and spaced notches of varying sizes and measurements according to any standard scale, such as inches, or of the metric system in centimeters, is continued around the marginal or peripheral edge surrounding the plate. As shown, the next tapered projection of triangular formation is indicated at 23 with an acute angled or V-shaped notch 24 having the edge 25 producing the hypotenuse and the edge 26 producing the base which in this instance is longer than the hypotenuse and an intervening marking corner or point 27 at the meeting point of the edges 21 and 25. This gives a linear measurement of one-half of an inch as marked on the gauge, but without again repeating it, it is to be understood that any other suitable size of notch, and consequently the measurement to be marked off, may be provided in any standard or desired scale. The next projection is indicated at 28 and like the projection or extension 12, is of obtuse angled formation with an intervening edge 29 between the edge 26 and a V-shaped or acute angled notch 30 to produce a short edge 31 forming the hypotenuse of the triangular notch with a long base edge 32 and resulting in a marking point or corner 33 of acute angled formation at the meeting point of the edges 29 and 31. As shown, this notch and marking point gives a measurement of three-eighths of an inch when used in the manner illustrated and as previously described in connection with the notches 14, 19 and 24. The base edge 32 forms one edge of an obtuse angled projection 34 having an intermediate edge 35 at obtuse angles to the edge 32 and another acute angled notch 36 forms an acute angled projection in connection with the edge 35 having a short edge 37 forming the hypotenuse of the triangular recess or notch 36 with a long edge 38 forming the base and resulting at the meeting point of the edges 35 and 37 in a marking point or corner 39 for giving a marking of five-sixteenths of an inch as shown. The edge 38 forms one side or edge of an obtuse angled projection 40 with an intermediate edge 41 at obtuse angles relative to the edge 38 and forming with a V-shaped notch or recess 42 a short edge 43 at acute angles to the edge 41 and forming the hypotenuse of a triangular

recess including an edge portion 44 at acute angles to the edge 43 and resulting in a marking point or corner 45 with the edges 41 and 43 at acute angles to each other and designed for giving a measurement of one-quarter of an inch or otherwise. The base edge 46 forms one side of an obtuse angled projection 46 with an edge portion 47 in such relation to the edge 44 and producing with an acute angled notch 48, a short edge 49 in similar relation to an edge portion 50 forming the other edge of the recess and producing a base while the edge portion 49 produces the hypotenuse of a right angled triangle erected on the base or edge portion 50 of the triangular notch, cut out or recess. This results in a marking point 51 at the meeting point of the edges 47 and 49 for giving a marking or measurement of three-sixteenths of an inch. The edge 50 forms one side of an obtuse angled projection or extension 52 with an edge portion 53 in similar relation to the edge 50 and forming in connection with the next adjacent acute angle notch 54 a short hypotenuse edge 55 opposed by a long base edge 56 and resulting in a marking point corner or edge 57 for giving a measurement or marking of one-eighth of an inch. The edge 56 forms part of an obtuse angled projection 58 with a V-shaped or acute angled notch 59 having an edge portion or base 60 forming the other side of the projection 58 and producing the hypotenuse 61 of a right angled triangle erected on the base of edge 60 of a triangular recess having a short side or base edge 60 opposed by the long edge or hypotenuse 61 forming the other side of the extension or projection 12 and resulting in a marking corner or edge 62 which, in this instance, gives a measurement of one inch from said corner 62 to the base 60 by a surface or line normal to said base or the largest shown in the particular gauge as illustrated. Of course, the measurements may vary and the device may be made in other sizes which in one form, as illustrated, is preferably about four and three-quarter inches by three and one-quarter inches so as to be relatively small and easily handled, placed in a pocket or stored when not in use. In each instance, the measurement is taken in right angles to the base edge portion, that is, with the plane of the surface to be marked not only normal to the plate of the gauge but at right angles to the length or plane of the base edge to the marking corner or edge across the notch or recess to form a substantially right angle triangle with the inner portion of the notch.

In Fig. 2 of the drawing, I have shown a slight modification in the marking of the gauge, in which the plate 10 bears an irregular outline 63 with pointers or arrows 64 adjacent each notch and pointing toward the same with the corresponding measurements for the particular notches adjacent thereto and within which said outline, pointers and markings are provided. In either form, the device is used by taking the work produced by the sheet or material 65 having the surface to be marked so that the edge 66 thereof from which the measurement is taken, is displaced against a base edge such as the base edge 44 as indicated in Fig. 1 of the drawing and with the surface or work extending perpendicular to the length or plane of said edge whereby the marking corner or point such as 45 will engage the surface 65 and may be moved along the same by gripping the plate of the gauge as seen in Fig.

1 to give the marking at a plurality of points or as a line 67 also as indicated in said view by cutting, scratching or digging into the metal or material of the work resulting in a mark, scratch or cut which is readily discernible and accurate. Hardened spring steel is preferably used in connection with the metal marking but as previously stated, the gauge or plate thereof may be of any other suitable material according to the use prescribed. From the foregoing, it is thought that the manner of use, operation and advantages of the device will be readily apparent especially to those skilled in the art and therefore further detailed description thereof is omitted. However, while it is optional, the outline 63 and measuring indications, either or both, may and preferably are of contrasting form or colors with respect to the gauge plate, and each other as well if desired, so as to be more easily seen or discerned, though they may be impressed, stamped, embossed, imprinted or otherwise formed or placed thereon, as it is thought will be readily understood. Also, any suitable marking means may be employed at the marking edges, corners or points to place a contrasting mark such as a line, dot, dash or otherwise on the sheet or surface 65 properly supported to receive the gauge there-

against at one or more edges as shown and described. The plate may also be said to be relatively circular, oval or egg shaped and tapered toward one end, and regular or irregular as desired.

5 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

10 15 Having thus described my invention, what I claim as new and desire to secure by Letters Patent is:

20 25 As a new article of manufacture, a marking gauge comprising a hardened flat plate with an acute angled notch having a marking corner at the end of at least one side thereof and forming a predetermined distance on a standard scale from the end of said side on a line perpendicular to the other side and forming a right angled triangle with said sides.

EDWIN JOHN ROOS.
